UNITED STATES PATENT OFFICE.

WALTER L. FORWARD, OF WEST BERKELEY, CALIFORNIA, ASSIGNOR TO BYRON JACKSON IRON WORKS, OF BERKELEY, CALIFORNIA, A CORPORATION OF CALIFORNIA.

TURBINE-PUMP.

987,976.

Specification of Letters Patent. Patented Mar. 28, 1911.

Application filed August 3, 1910. Serial No. 575,328.

To all whom it may concern:

Be it known that I, WALTER L. FORWARD, citizen of the United States, residing at West Berkeley, in the county of Alameda 5 and State of California, have invented new and useful Improvements in Turbine-Pumps, of which the following is a specification.

My invention relates to improvements in 10 that class of apparatus known as high pressure turbine pumps.

It consists essentially in a means for automatically balancing the runner or impeller, so called, so as to prevent undue movement axially in either direction.

It also includes the combination of parts and details of construction which will be more fully explained by reference to the accompanying drawing, in which—

20 Figure 1 is a longitudinal section of a high pressure turbine with automatic balancing means. Fig. 2 is a section through chamber 7 showing the pumping vanes.

In pumps and apparatus of this class the 25 effect of the suction at the inner end and the pressure at the discharge end of the apparatus produces a thrusting action upon the runners or impellers which are revolved within a casing in such a manner as to raise 30 and discharge the liquid. Various means are employed to balance this constantly varying pressure recurring during the operation of the pump, such means being technically termed "balance plugs."

35 It is the object of my invention to provide automatically operating means for equalizing the pressures upon opposite sides of the impeller, and to cause it to constantly tend to remain in a central position; this being 40 applicable to single or a series of pumps.

As shown in the present drawings, A is a casing adapted to contain a runner or impeller 2 which is mounted upon a shaft 3, one journal box of which is shown at 4. At 45 one end of the casing, as at 5, connection is made with the source from which liquid is to be drawn.

3' is the suction inlet.

The rapid revolution of the impeller within 50 the casing effects a suction to draw the

liquid into the apparatus and by centrifugal force to throw it outward into the annular and discharge portion 6 of the casing. The vanes of the impeller revolve in a chambered head, from which head a sleeve 8 extends concentric with the shaft 3. Within this sleeve is fitted a tubular plug 9 which is secured and adjusted by studs and set nuts 10. Within this plug suitable packing 11 is interposed between the plug and the shaft to 60 form a tight joint, and 12 is the gland which abuts and retains the packing in place.

7 is a chamber integral with the back of the runner and having pumping vanes 7'.

13 are ports formed in the rim of the 65 chamber 7 and opening into the discharge portion 14 of the casing; and 13^a are ports communicating with the chamber 15. The chambers 14 and 15 are formed respectively 70 between the runner or impeller and the interior of the casing, and between the impeller and the cover 16; and the ports are so located with relation to these chambers that end movement of the impeller opens and 75 closes these ports to a greater or less degree.

The operation of the apparatus would then be as follows: Should the impeller 2 move toward the suction inlet 3' of the pump, due to an accumulation of pressure in the chambers 14 and 15 which connect 80 with the discharge portion of the apparatus, the vanes in the chamber 7 would act as a pump as soon as the ports 13^a were opened by the movement of the impeller away from the cover 16 and plug 9. The vanes in the 85 chamber 7 would then draw a supply of liquid from the chamber 15 and would force the same into the chamber 14 which communicates with the discharge, thus relieving the pressure in the chamber 15 to such an 90 extent as to permit the impeller 2 to move toward the cover 16 and the plug 9. The pumping effect of the vanes in the chamber 14 would tend constantly to reduce the pressure in the chamber 15, and due to this action, the impeller would automatically locate and remain in a central position. The pumping effect of the vanes in the chamber 7 is controlled by means of the plug 9, which may be adjusted with relation to the moving 100

parts by means of the studs or set screws and nuts 10, as previously stated. Water gets into chamber 15 by the back pressure of the head pumped against; this head pressure 5 sure from the involute 6 and chamber 14 seeking admission to the chamber 15 through the running joint provided by the rim 17 of the back side of the runner and the annular flange 18 of the casing. This 10 back pressure through the running joint will accumulate in chamber 15 until the thrust from that end moves the impeller sufficiently to open communication between the pressure chamber 15 and the vacuum chamber 7 15 through the space 13^a around the end of the female plug 9. This relief pressure is then discharged from chamber 7 through the ports 13 into the pump discharge and outside the impeller. This is to be distinguished 20 from delivering the excess leakage water from the pressure chamber 15 into the suction side or center of the runner. The runner may be shifted lengthwise of shaft 3, so as to vary the point of equilibrium of the 25 runner by moving the plug 9 in or out.

Having thus described my invention, what I claim and desire to secure by Letters Patent is—

1. An automatic balancing means for a 30 turbine pump, such means comprising a casing having inlet and discharge passages, a runner or impeller mounted upon a shaft and revoluble within the casing, said impeller and casing forming chambers within 35 which liquid pressure may accumulate, and said impeller having ports near its circumference and axis forming communication between said chambers and means whereby the ports are automatically controlled 40 by the endwise movement of the runner.

2. In a turbine pump, a casing with a centrally disposed inlet, an annular peripheral discharge and a chambered head opposed 45 to the inlet, a runner or impeller revoluble within the casing, having a rim extension and vanes fitting the head chamber, said rim-extension and the axial portion of the runner having ports communicating respectively 50 with the head chamber and with the discharge, and means controlling said ports by the endwise movement of the runner.

3. In a turbine pump, a casing with a centrally disposed inlet, an annular peripheral discharge, and a chambered head opposed to the inlet, a runner or impeller revoluble within the casing, with a rim-extension and vanes fitting the head chamber, said rim-extension having ports communicating 55 respectively with the head chamber and with the discharge and adapted to control the discharge therethrough by the end movement of the runner, a sleeve, and an axially adjustable tubular plug within the

sleeve, said runner having a port in line with 65 and controlled by the plug, and through which sleeve the impeller shaft extends and is revoluble.

4. In a turbine pump, a casing with a centrally disposed inlet, an annular peripheral discharge and a chambered head opposed to the inlet, a runner or impeller revoluble within the casing, having a rim-extension and vanes fitting the head chamber, said extension having ports communicating respectively with the head chamber and with the discharge and adapted to control the discharge therethrough by the end movement of the runner, a tubular plug within which the impeller shaft is revoluble, said runner 80 having a port in line with the plug and controlled thereby, and means to adjust the plug in the direction of its length.

5. In a centrifugal pump, the combination of a casing, an impeller therein, means forming a pressure chamber on one side of the runner, an annular vacuum chamber in the runner adjacent to the pressure chamber, and means for automatically controlling communication between the pressure chamber and vacuum chamber, said means comprising fixed members relatively to which the ports are moved to vary the port opening, by the end movement of the runner, said vacuum chamber having communication 95 with the discharge of the pump outside of the impeller and inside the casing.

6. The combination in a centrifugal pump, of a casing, an impeller therein having an inlet and a discharge, said impeller having 100 an annular vacuum chamber on one side, said vacuum chamber having a running joint with a flange of the pump case, the impeller and pump case inclosing a pressure chamber which is in communication with 105 the pump discharge through the running joint, said pressure chamber and vacuum chamber having communication approximate to the axis of the runner, and said vacuum chamber having ports controlled by 110 said running joint, and which ports when uncovered by the running joint open directly into the discharge.

7. In a centrifugal pump, the combination of a case having a central inlet and peripheral discharge, a shaft, an impeller in the case on the shaft and having a running joint with the case, means on the case and on the side of the impeller opposite the suction inlet to inclose a pressure chamber receiving 115 leakage water from the discharge through the running joint between the impeller and case, a vacuum chamber in the impeller between the suction inlet and the pressure chamber, means whereby on the accumulation of an excess pressure in the pressure chamber the excess of water therein may be discharged through the vacuum chamber.

into the pump discharge and exterior to the suction passages in the impeller, and means including an adjustable plug fixed in line with one of the discharges and varying said discharge automatically in response to the degree of end movement of the runner for regulating said excess pressure.

In testimony whereof I have hereunto set my hand in the presence of two subscribing witnesses.
